UNITED STATES PATENT OFFICE

160,148

SET OF PLAYING CARDS

James E. Clarke, Long Beach, Calif.

Application June 17, 1949, Serial No. 3,364

Term of patent 14 years

(Cl. D34—13)

To all whom it may concern:

Be it known that I, James E. Clarke, a citizen of the United States, residing at Long Beach, in the county of Los Angeles and State of California, have invented a new, original, and ornamental Design for a Set of Playing Cards, of which the following is a specification, reference being had to the accompanying drawing, forming a part thereof.

Figures 1 through 9 are face views of the respective suits of a set of playing cards, showing my new design;

I claim:

The ornamental design for a set of playing cards, as shown.

JAMES E. CLARKE.
